VAPOR ELECTRIC DEVICE

John L. Boyer, Pittsburgh, Pa., assignor to Westinghouse Electric Corporation, East Pittsburgh, Pa., a corporation of Pennsylvania

Application June 30, 1949, Serial No. 102,284

4 Claims. (Cl. 250—27.5)

1

My invention relates to a vapor electric device and particularly to a mercury arc device operating at high temperature and pressure.

In the operation of mercury arc devices, the arc drop and electrode losses appear as heat. The maximum rating of the device is therefore determined by the ability to dissipate these losses.

Water and air-cooled tubes of the present design usually have temperature limits between 50° C. and 60° C. Since most rectifiers are required to operate with water or air temperatures up to 35° C., it is difficult to obtain sufficient cooling at higher ratings. Consequently, the necessity for a two-hour overload run at 150% of the rating usually determines the normal or static rating of the tube. Obviously, if an increase of transfer of heat to the cooling medium could be increased, the rating of the tube could likewise be increased.

The important factor which limits the permissible temperature of the usual design of tubes, particularly of pool type tubes, is a rapid increase of the mercury vapor pressures with temperature so that the breakdown voltage decreases very rapidly with increase in temperature. As is well known, the breakdown pressure of mercury vapor has a typical so-called pressure distance curve, that is the distance in centimeters times the pressure in millimeters of mercury gives a pressure distance factor, and it is well known that at a very small pressure distance factor, the breakdown characteristic of mercury vapor is very high, and normal tubes are operative at a pressure distance factor of the order of 1 to 2 with a breakdown of several thousand volts. However, with increase in pressure or distance or both, the pressure distance factor rapidly increases and the breakdown voltage rapidly decreases so that in normal operating voltage a high rate of arc back occurs and prevents operation with a high vapor pressure distance ratio.

According to my invention, I provide a tube having long distances between the anode and any conducting surfaces at cathode potential so that the distance is of at least the order of 5 centimeters, and the pressure is increased by operating the tube at a temperature of the order of 200° C. to 300° C. so that a very high pressure is maintained in the tube. This high pressure times the line distance produces a very high pressure distance factor, and the tube operates on the outside end of the pressure distance curve so that again a very high breakdown characteristic is obtained. These high pressure tubes have a further advantage in that very simple internal struc-

2

ture permits a minimum of construction cost while the large quantity of vapor available permits the carrying of large currents with a minimum of arc loss. Because of the simplicity of the interior structure of the tube, the arc drop also will be at a minimum.

A further advantage lies in the fact that as the tube operates at a very high temperature the transfer of the arc and electrode losses through the cooling medium is much more easily accomplished, and large ratings can be satisfactorily cooled in relatively small cooling surfaces.

When tubes operate at very low pressures, sometimes the vapor available fails to carry the current and results in surging or momentary high voltages in the tubes or their associated circuits. With high pressure tubes, a large quantity of vapor is available at all times to carry the current, and consequently little or no surging is to be expected. Further, because of the high current carrying capacity of the vapor, large overloads, even to short-circuit, may be carried without danger of damage to the tube.

It is accordingly an object of my invention to provide a simplified tube structure.

It is a further object of my invention to provide a mercury arc discharge device operating at high temperatures.

It is a further object of my invention to provide a mercury arc discharge device having high current characteristics.

Other objects and advantages of my invention will be apparent from the following detailed description taken in conjunction with the accompanying drawing, in which:

Figure 1 is a sectional elevation of a mercury arc device according to my invention; and

Fig. 2 is a diagrammatic presentation of a typical pressure distance breakdown curve.

In the exemplary embodiment of my invention, the vapor electric device comprises a metallic container 1 having a pool of mercury providing a mercury cathode 2 and cooperating with the mercury cathode is a suitable anode 3, preferably of graphite. The anode 3 and its stem 4 are widely spaced from all of the metallic or conducting surfaces of the container 1 so that the minimum distance from the anode 3 to any conducting surface at cathode potential is at least 50 of the order of 5 centimeters.

Suitable heating devices, herein shown as resistance type electric heaters 5, are provided around the body of the container 1 and are energized to maintain the temperature of the device 55 of the order of 210° C. In order to facilitate

vaporization of the mercury cathode, a suitable resistance heater 6 is preferably attached to the cathode plate 7. By properly energizing these heating elements 5 and 6, a temperature of the order of 210° may easily be maintained, and a high mercury vapor pressure results.

In order to prevent condensation of mercury vapor on the anode 3 or the insulating bushing 8, it is desirable to provide a heating element 9 directly attached to the anode stem 4. In this manner the entire device will be maintained at operating temperatures providing a high vapor pressure, together with a high pressure distance characteristic.

Suitable cooling means should be provided for dissipating the losses which occur in the tube when operating at high load. For this purpose I have shown a jacket 12 surrounding the tube 1, and a cooling fluid, such as air, may be circulated therethrough by any suitable means (not shown). If desired, the heating elements 5, 6 and 9 could obviously be thermostatically controlled so that the heating elements would be dispensed with during operation at sufficient load to maintain the device at the desired high operating temperature. Likewise, it is apparent that thermostatic control could be applied to the device for circulating the cooling medium so that the cooling medium would only be applied in the event of an unusually high temperature occurring in the device.

The operation of the device will best be understood by a consideration of the pressure distance curve of Fig. 2. While a very high breakdown characteristic may be maintained with a very low pressure distance ratio, it is apparent that with a large distance, such as occurring in the simple tube according to my invention, a normally very low breakdown characteristic could be found. However, by heating the container 1 and the mercury therein so that a very high pressure obtains a pressure distance characteristic having an inverse breakdown potential of substantially the same order as the very low pressure distance characteristic can be obtained.

For exemplary reasons, I have shown a preferred embodiment of my invention and described the same to the best of my present ability. I desire it to be understood that such showing and description are exemplary only and that changes and modifications can be made therein without departing from the true spirit of my invention and the scope of the appended claims.

I claim as my invention:

10. 1. A vapor electric device comprising a container, a pool of vaporizable cathode material in said container, an anode in said container, said anode being widely spaced from any conducting surfaces at cathode potential and a heater 15 supplying heat to said cathode material for maintaining a high vapor pressure in said container.
20. 2. A heavy duty vapor electric device comprising a container; a vaporizable reconstructing cathode in said container, an anode in said container, said anode being spaced at least five centimeters from any conducting surfaces at cathode potential and a heating device for maintaining a vapor pressure of the order of forty mm. of mercury.
25. 3. A vapor electric device comprising an evacuated container, a quantity of vaporizable cathode material in said container; an anode in spaced insulated relation in said container, heating means maintaining a high vapor pressure in said container.
30. 4. A vapor electric arc discharge device comprising an substantially evacuated container; an anode and a cathode in said container, the parts of said device which are at anode potential being widely spaced from the parts which are at cathode potential; a quantity of mercury in said container; heating means for vaporizing said mercury to maintain said device operating in a high pressure distance region.
